UNITED STATES PATENT OFFICE

2,464,255

GAS BURNER

Joseph F. Mustee, Cleveland, Ohio

Application June 28, 1945, Serial No. 601,971

7 Claims. (Cl. 158—116)

1

An object of my invention is the provision of a gas burner having a plurality of outwardly extending conduits or jets fed by gas through a plurality of openings formed by a slotted disk seating between two members which when fitted together define the outwardly extending conduits or jets.

Another object of my invention is the provision of air intake openings for the conduit means or jet in which the openings are adjusted as to their size to vary the mixture of gas and air.

Another object of my invention is the provision of admitting the flow of gas into a plurality of outwardly extending conduits or jets and of mixing the air with the gas in the conduits or jets, whereby the burner is capable of producing a blue or heating flame even when the gas supply is cut down to a very low pressure.

Another object of my invention is the provision of a gas burner which is simple and inexpensive to manufacture and in which several parts can be readily assembled and also changed so as to vary the amount of gas admitted to the plurality of outwardly extending conduits or jets.

Other objects and a fuller understanding of my invention may be had by referring to the following description and claims, taken in conjunction with the drawings, in which:

Figure 1 is a top plan view of a burner embodying the features of my invention;

Figure 2 is a vertical cross-sectional view of my gas burner taken along the line 2—2 of Figure 1;

Figure 3 is a cross-sectional view taken along the line 3—3 of Figure 2;

Figure 4 is a cross-sectional view taken along the line 4—4 of Figure 2;

Figure 5 is a view of the underneath side of my burner; and

Figure 6 is a view similar to Figure 2, but showing a modification of the air intake openings for admitting air to the plurality of outwardly extending conduits or jets.

With reference to the drawing, my gas burner is adapted to be connected to a gas supply pipe 10 by means of an attachment coupling 11 which is threadably connected to the gas supply pipe 10. My burner comprises generally a tubular member 12 having a conical annular flange 14 extending outwardly therefrom, a conical annular member 15 fitting in the conical annular flange 14, and a disk 17 seated between the conical annular flange 14 and the conical annular member 15. The tubular member 12 and the attachment coupling 11 have interfitting shoul-

2

ders at 32 for making a gastight connection therebetween when the burner is assembled by means of a connecting bolt 22 which threadably engages a central lug 23 constituting a part of the attachment coupling 11. Surrounding the central lug 23 are a plurality of openings 24 through which the gas flows upon leaving the gas supply pipe 10.

The upper end of the tubular member 12 flares outwardly and is provided with a distributing outlet end 13 across which the disk 17 extends. The marginal edge of the disk 17 is indicated by the reference character 18 and is provided with a plurality of outwardly extending slots 19. The marginal edge portion 18 of the disk 17 is seated between the outlet end 13 of the tubular member 12 and a peripheral edge portion 33 of the conical annular member 15, whereby the slots in the disk provide a plurality of openings through which the gas may flow.

The conical annular member 15 constitutes a closure means for the outlet end 13 of the tubular member 12. The conical mating surfaces of the conical annular flange 14 and the conical annular member 15 are respectively provided with semi-circular grooves 30 and 31 which when the two flanges are secured together by the connecting bolt 22 provide a plurality of conduits or jets for the gas. The slots 19 in the disk 17 are in alignment with the conduits or jets, whereby the slots in the disk provide a plurality of openings through which the gas passes upon leaving the outlet end 13 of the tubular member 12 and upon entering the conduits or jets. The slots of the disk may be held in alignment with the conduits or jets by any suitable means and as illustrated in Figure 3 the central portion of the disk 17 is provided with a triangular opening 20 which fits over a triangular boss 21 on the underneath side of the conical annular member 15 whereby the disk cannot turn after it is once mounted in position. When the connecting bolt 22 is turned down tight the two conical flanges fit tight against each other to define the conduits or jets without any clearance between the mating surfaces. The peripheral edge portion 33 of the conical annular flange 15 which seats or makes engagement against the marginal edge portion 18 of the disk may be slightly recessed to receive the disk whereby the two flanges may make a tight fit therebetween when the connecting bolt 22 is turned down tight. The amount of gas which flows through the slots in the disk may be determined by the thickness 55 of the disk. For burners which require a small

amount of gas the disk may be of relatively thin sheet-like material and for burners requiring a considerable amount of gas the disk may be made of thicker material. In my invention the seated recess provided in the conical annular member 15 may be made to receive the disk of the thinnest dimension and for thicker disks a slight clearance may be present between the two annular flanges when the connecting bolt 22 is turned down. In my invention the outer edge of the flanged members are arranged to contact first so that when a thicker disk is used the small clearance or crack which appears between the flanges is present only in the region near the disk and there will be no clearance or crack between the mating flanges at the mouth of the conduits or jets. The difference in the thickness of the disk to regulate the amount of gas flow may be only in the neighborhood of a few thousandths of an inch so that when a thicker disk is used the clearance between the two flanges in the locality adjacent the disk is only in the neighborhood of a few thousandths of an inch.

As illustrated in Figure 2 of the drawing, the bottom or the throat end of the conduits or jets is provided with air intake openings 34. The amount of air which flows into the air intake opening 34 is regulated by an air adjusting sleeve 35 having a conical flange 36 which fits against the underneath side of the conical annular flange 14. The conical flange 36 is provided with a plurality of air adjustment holes 37 and the alignment of the air adjustment holes 37 with the air adjusting or intake opening 34 regulates the amount of air admitted to the conduits or jet openings. When the conical flange 36 is properly adjusted the adjustment may be maintained in a fixed position by operating the set screw 38 which holds the air adjusting sleeve and conical flange in a fixed position. The mixture of the gas and air determines the nature of the flame and when adjusting the amount of air the operator observes the nature of the flame and when the flame is of the proper kind the set screw 38 is then set to maintain the adjustment.

In Figure 6 I show a modification of the air intake adjustment in that the conical annular member 15 is provided with air intake openings 41 which are adjusted as to size by the air adjusting plate 42 held in a fixed position by the connecting bolt 22. The air adjusting plate 42 has a conical flange 43 and the conical flange is provided with a plurality of air adjusting holes 44 which when properly aligned with the air intake openings 41 determine the amount of air admitted to the conduit or jet opening and thereby regulating the nature of the flame.

In the drawings, I have illustrated the conical annular flange 14 and the conical annular member 15 as being made of castings but it is also understood that these two parts may be made of stamped material, which when the two parts are secured together define outwardly extending conduits or jets. In order to distribute the flame emitting from the conduits or jets the conduits are alternately of different lengths. The long conduits or jets are indicated by the reference character 25 and the short conduits or jets are indicated by the reference character 26, and these are alternately disposed around the burner. As shown in Figure 6, the ends of the conduits or jets are provided with upwardly directed baffles 45 for directing the flame upwardly. The baffles are integrally formed with the conical annular

flange 14 and may be at any suitable angle for directing the flames as they leave the conduits or jets. The baffles may also be applied to the burner shown in Figure 2.

5 Although I have described my invention in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

15 1. A gas burner comprising a tubular member for feeding gas, said tubular member having an outlet end provided with an annular flange, an annular member fitting against said annular flange, said annular flange and said annular member having mating surfaces, said mating surfaces each defining a plurality of outwardly extending conduit grooves with the conduit grooves of the annular flange in alignment with the conduit grooves of the annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, said annular flange having air intake openings extending respectively into said conduit means.

40 2. A gas burner comprising a tubular member for feeding gas, said tubular member having an outlet end provided with an annular flange, an annular member fitting against said annular flange, said annular flange and said annular member having mating surfaces, said mating surfaces each defining a plurality of outwardly extending conduit grooves with the conduit grooves of the annular flange in alignment with the conduit grooves of the annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, said annular flange having air intake openings extending respectively into said conduit means.

45 3. A gas burner comprising a tubular member for feeding gas, said tubular member having an outlet end provided with a first annular member, a second annular member fitting against said first annular member, said first annular member and said second annular member having mating surfaces, said mating surfaces each defining a plurality of outwardly extending conduit grooves with the conduit grooves of the first annular member in alignment with the conduit

50 60 65 70 75 80 85 90 95

grooves of the second annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, at least one of said annular members having air intake openings extending respectively into said conduit grooves.

4. A gas burner comprising a tubular member for feeding gas, said tubular member having an outlet end provided with an annular flange, an annular member fitting against said annular flange, said annular flange and said annular member having mating surfaces, said mating surfaces each defining a plurality of outwardly extending conduit grooves with the conduit grooves of the annular flange in alignment with the conduit grooves of the annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, said annular member having air intake openings extending respectively into said conduit grooves.

5. A gas burner comprising a tubular member for feeding gas, said tubular member having an outlet end provided with a first conical annular member, a second conical annular member fitting against said first conical annular member, said first annular member and said second annular member having conical mating surfaces, said mating surfaces each defining a plurality of outwardly extending conduit grooves with the conduit grooves of the first annular member in alignment with the conduit grooves of the second annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, at least one of said annular members having air intake openings extending respectively into said conduit grooves, and means for adjusting the size of the air intake openings to vary the mixture of the gas and air, said pair of aligned conduit grooves being alternately of different lengths.

6. A gas burner comprising a tubular member for feeding gas, said tubular member having an

outlet end provided with a first conical annular member, a second conical annular member fitting against said first conical annular member, said first annular member and said second annular member having conical mating surfaces, said mating surfaces each defining a plurality of outwardly extending conduit grooves with the conduit grooves of the first annular member in alignment with the conduit grooves of the second annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, at least one of said annular members having air intake openings extending respectively into said conduit grooves, and means for adjusting the size of the air intake openings to vary the mixture of the gas and air, said pair of aligned conduit grooves being alternately of different lengths.

7. A gas burner comprising a tubular member for feeding gas, said tubular member having an outlet end provided with a first annular member, a second annular member fitting against said first annular member, said first annular member and said second annular member having mating surfaces, said mating surfaces each defining a plurality of outwardly extending conduit grooves with the conduit grooves of the first annular member in alignment with the conduit grooves of the second annular member, each pair of aligned conduit grooves constituting an individual jet through which gas passes, a disk having its marginal edge portion provided with a plurality of outwardly extending slots, said disk extending across the outlet end of said tubular member and having its marginal edge portion seating between said mating surfaces with the slots in the disk respectively in alignment with the conduit grooves, whereby said slots in the disk provide a plurality of openings through which the gas passes upon leaving the outlet end of the tubular member and upon entering the conduit grooves, at least one of said annular members having air intake openings extending respectively into said conduit grooves, and baffle means at the ends of the conduit grooves for directing the flames emanating from the conduit grooves.
